UNITED STATES PATENT OFFICE.

JOHN ROBERT REID AND JOHN DEASE BELL, OF VANCOUVER, BRITISH COLUMBIA,
CANADA.

DUCK-DECOY.

1,290,359.

Specification of Letters Patent.

Patented Jan. 7, 1919.

Application filed November 19, 1917, Serial No. 202,801. Renewed December 4, 1918. Serial No. 265,259.

To all whom it may concern:

Be it known that we, JOHN ROBERT REID and JOHN DEASE BELL, both subjects of the King of Great Britain, and both residents of 5 the city of Vancouver, in the Province of British Columbia, Canada, have invented certain new and useful Improvements in Duck-Decoys, of which the following is a specification.

10 Our invention relates to improvements in decoys, with particular reference to those employed in duck shooting, and the object of our invention is to provide a device of this nature of such construction that a number 15 of them can be compactly parceled together and conveniently transported from place to place personally by the user, which device is effective in use, of light weight, simple in construction, and capable of being 20 manufactured and sold at a low cost.

We attain this object by the construction illustrated in the accompanying drawings in which—

Figure 1 is a side elevation of the device.

25 Fig. 2 is a cross section taken on the line *a—b* of Fig. 1.

Similar figures of reference indicate similar parts throughout the several views.

The decoy, indicated by the numeral 1, is 30 formed to shape out of a flat piece of board or other buoyant material, preferably about three-quarters of an inch thick, so as to represent, when viewed from the side, the profile of a duck.

35 At a suitable point in the body 1 is a hole 2 through which is passed loosely a wire 3, which wire is bent over on each side of the body 1 and clear of the same so that its ends extend downwardly a suitable distance below the body, and to the ends of the wire is secured a weight 4, which weight may consist of a piece of sheet lead wrapped several times around the wire and prevented from detachment therefrom by turning up 40 the extremities of the wire under the lower edge of the weight, as indicated at 5 and 6 in Figs. 1 and 2. Any other suitable form of weight and means of attaching it to the body 1 may, however, be employed. The 45 weight is adapted to maintain the decoy on

edge when floating whereby the profile itself is ballasted.

From the foregoing, therefore, it will be seen that the decoy simply consists of the profile of a duck formed of thin buoyant 55 material to which is swingably attached a weighted wire loop, indicated by the numeral 7, by means of which it may be maintained in a vertical position in the water when placed therein. For convenience of 60 packing and transportation the wire loop 7 is of such length that it may be swung upwardly from its operative position, indicated in full in Fig. 1, to carry the weight 4 under the stern of the decoy, as indicated 65 by the dotted lines in Fig. 1, and in order to hold the loop in this position the width between the wires of the loop adjacent the weight is made slightly less than the thickness of the decoy body so that they, the 70 wires, will be sprung apart slightly in the act of swinging the loop to the dotted position shown so as to grip the decoy body sufficiently to hold the loop and the weight 75 in the inoperative position.

What we claim as our invention is:—

1. A single duck decoy formed as a profile out of one piece of thin buoyant material ballasted so as to float on edge without the use of extraneous means.

2. A single duck decoy formed as a profile out of one piece of thin buoyant material and a weight swingably connected thereto and depending therefrom so as to maintain the decoy on edge when floating whereby the 85 profile itself is ballasted without the use of extraneous means.

3. A duck decoy formed as a profile out of one piece of thin buoyant material and a depending weight directly connected to the 90 said profile by means of an inverted U-shaped member so as to maintain the same on edge when floating without the use of extraneous means, said weight being adapted to be swung under the stern of the profile 95 when inoperative, with one arm of the U-shaped member on each side of the profile.

4. A single decoy duck formed as a profile of thin buoyant material having an aperture therethrough abaft its vertical center line 100

and on approximately its horizontal center line, an inverted U-shaped element passing through said aperture, and depending from the decoy, and a weight carried by the extremities of the element to maintain the decoy on edge when floating whereby the profile itself is ballasted, said element being

adapted to be swung under the stern of the decoy body when inoperative.

Dated at Vancouver, B. C., this 25th day 10 of October, 1917.

JOHN ROBERT REID.
JOHN DEASE BELL.
